3 SHEETS—SHEET 1.

FIG. 1.

Technical drawing of a circular component, likely a bearing or seal, with the following features labeled:

- Outer ring: 22, 23, 24, 25, 26, 27, 28, 29, 30, 31, 32, 33, 34, 35, 36.
- Inner ring: 24, 25, 26.
- Shaft: 34, 35, 36.
- Witnesses: WITNESSES.

A diagram of a target with concentric rings. The innermost ring is divided into four quadrants, each containing a number: 44 at the top, 43 at the bottom, 41 on the left, and 42 on the right. The next ring out is divided into four quadrants, each containing a number: 34 at the top, 35 at the bottom, 31 on the left, and 32 on the right. The outermost ring is divided into four quadrants, each containing a number: 40 at the top, 29 at the bottom, 30 on the left, and 31 on the right. The segments are shaded with diagonal lines.

UNITED STATES PATENT OFFICE.

GEORGE M. RICHARDS, OF PHILADELPHIA, PENNSYLVANIA.

VALVE FOR AIR-COMPRESSORS.

1,251,420.

Specification of Letters Patent. Patented Dec. 25, 1917.

Application filed August 20, 1914. Serial No. 857,790.

To all whom it may concern:

Be it known that I, GEORGE M. RICHARDS, a citizen of the United States, residing at 4438 N. 15th St., Philadelphia, in the county of Philadelphia and State of Pennsylvania, have invented a certain new and useful Valve for Air-Compressors, of which the following is a specification.

My invention relates to valves capable of use at the inlet and discharge ends of air compressor cylinders.

The purposes of my invention are to stiffen the valve against strains; maintain a rigid plane of face for the valve at all times; press the valves reliably against their seats by means coöperating with the channeled structure of the valve; utilize posts which space a base member and a cap of a preferably removable valve unit for the further purpose of guiding the valves, coöperating for this purpose with flanges at the edges of the valve; increase the circumferential extent of valve opening; keep the clearance of the valve low; supply separately movable closures for different valve openings; allow movement of oscillation or rotation of the different valves independently of each other; cup the engaging faces of the valves between the valve edges so that the projecting portions only need be finished; place stiffening flanges in line with the engaging valve edges; and, in such a structure, make the valve seat accessible for finishing to the best advantage.

Further purposes of my invention will appear in the specification and are set out in the several claims thereof.

I have preferred to illustrate my invention by forms thereof which, in practice, have proved to be practicable, efficient and inexpensive and which at the same time well illustrate the principles of my invention.

Figure 1 is a central longitudinal section of an air compressor cylinder, taken through the inlet and discharge ports.

Fig. 2 is a central section through the axis of the discharge valve shown at the right hand in Fig. 1 with a portion of the cylinder adjoining.

Figs. 3 and 4 are sections of Fig. 2 taken upon the lines 3-3 and 4-4 respectively, looking in the direction of the arrows.

Figs. 5 and 6 are sections corresponding to that of Fig. 2, showing a second form of my invention, with parts in different positions.

Figs. 7 and 8 are sections of Fig. 5 taken upon the lines 7-7 and 8-8 respectively, looking in the directions of the arrows.

Figs. 9 and 10 are central sections through the axis of the inlet valve shown in Fig. 1, with a part of the cylinder adjoining, the parts being in different positions.

Figs. 11 and 12 are sections of Fig. 9 taken upon lines 11-11 and 12-12, respectively, looking in the directions of the arrows.

Similar numerals of reference indicate like parts in the drawings.

Where light material, such as sheet metal, is utilized for a valve and the same sheet is intended to close a number of independent valve openings at different distances from the center or along the length of the sheet, difficulty is experienced not only in securing an absolutely flat sheet or plate for co-operation with the several valve seats, but in maintaining it against distortion and in maintaining the seats within the same plane for co-operation with it. For this reason I have preferred to use separate valve closures for separate valve openings.

In the forms shown, my valves are of circular contour and this is quite desirable, because of the free shifting circumferentially permitted with this form of valve, which may even move completely about its axis without interference with the valve action; but this form of valve is not essential, in that some of the advantages of my invention would be obtainable with other contours of valve opening.

I have shown my invention as applied to the discharge and inlet valves of an air compressor cylinder 1; having water cooling space 2 and heads 3 and 4 and containing piston 5 and piston rod 6.

For convenience I will describe the invention as applied to cylinder ports or openings against which removable valve units are clamped or secured, each valve unit carrying both the valve seats and the coöperating valve structure.

Both of the ports or openings 7 are provided with sealing faces 8, here shown as annular and as located at the side of the cylinder, for the reception of the removable valve units. These faces are engaged by corresponding annular edge faces 9 of the removable valve units 10 and 10' providing inlet and discharge for the cylinder. These valve units may be inserted and withdrawn

through openings 11, 11' which are threaded at 12, 12' to receive threaded plugs 13, 14. The plug 13 provides free air inlet while that at 14 closes the opening. Each plug supports a set screw, 15, 16 respectively, by which the valve units are held together and pressed against the sealing faces 8. Air passes through openings 17 in plug 13 into the space 18 about the valve unit 10, while the space 19 about the discharge valve unit 10' communicates with a discharge pipe 20.

The structures of the two valve units are similar but the valves face oppositely with the result that the valve seats are carried by the base of one and by the cap or cover of the other.

Taking up the discharge valve first:— The valve is made up functionally of four main parts, namely, the base 21 carrying the valve seats and certain spacing and supporting posts hereinafter described, the several valves, which may be of any desired number and are here indicated at 22, 23 and 24, the cap or cover 25 through which the set screw 16 holds the removable valve element in position and the means for resiliently closing the valves, here springs numbered 26, 27 and 28.

The engagement of face 9 of base 21 with the contact face of the cylinder, previously indicated, completely closes the port or opening 7 into the cylinder at this point except as valve openings may be free for air passage. These valve openings are preferably of annular contour and extend throughout the entire circumference except as they are necessarily interrupted by ties 29 and 30 by which the several adjoining rings 31, 32 and 33 are connected and supported.

About the base at any suitable intervals are located a series of posts 34, 35 and 36, which in the form shown in Figs. 2, 3 and 4 are rigidly attached to and preferably integral with the base, rising from the rings 31, 32 and 33 to engage with the cap or cover annulæ along any parts of the annular surfaces as 37, 38 and 39 for the purpose of transmitting pressure from the cap or cover member to the base and affording a firm and even rest for the cap or cover.

The width of the posts 34, 35 and 36 is less than the width of the rings upon which they rest or with which they are integral, 55 in order that the edges of the rings 31, 32 and 33 may be available as valve seats, arranged in circular pairs 40 and 41, 42 and 43 on opposite sides of the respective annular valve openings and the single seat 60 44, for coöperation with corresponding valve edges upon the valves 22, 23 and 24.

It will be evident that these several seats may be machined upon a lathe or mill even if the posts be integral with the rings upon 65 which they are supported.

The valves are separate in order that there may be separate movement of the valves both toward and from the seats and, as wear may determine, in circular movement about the seats, the freedom of movement in this direction coöoperating both to avoid unevenness of wear and to facilitate coöperation of the parts toward tightening the joint as long as possible where wear has already taken place.

The outer valves illustrated are similar annulæ and the inner valve is of cup formation, coöoperating with a single circular valve seat 44 only.

The valves are preferably made of sheet metal, pressed to shape and are provided with strengthening flanges at or near their edges, shown at 45, 46, 45', 46', 45² for the purpose of giving stiffness to the annulæ and cup and, where they are in line with the edges, for the further purpose of coöperating with the adjoining side surfaces of the posts 34, 35 and 36 in order to guide the annulæ.

There is also an advantage in having the stiffening flanges directly in line, axially, with the engaging surfaces of the valves and seats.

The operative faces of the several valves are slightly depressed or grooved annularly for the purpose of reducing the amount of surface which must be finished to a plane and at the same time reducing the difficulty of accurate finishing.

The valves are pressed to their duty by 100 the springs 26, 27 and 28 which are adapted to rest in suitable recesses within the cover 25. Obviously, the spring will continue to coöperate with the channeled sides of the annular valves notwithstanding that the 105 valves may move circumferentially.

The space located circumferentially between the outer posts 34 is open and the cover may likewise be apertured as at 47, 47' for the purpose of allowing free egress 110 for the discharged air into the space 10.

In the form shown in Figs. 5, 6, 7 and 8, the parts, as well as the functions of the parts, are intended to be identical with those shown in Figs. 2, 3, and 4, except for 115 the fact that the posts 34', 35' and 36' are attached to or integral with the cover 25' and rest within preferably annularly depressed spaces 48, 48' and 49 within the rings 31', 32', 33'. Annular depressions result in annular relatively projecting valve seats 40', 41', 42', 43' and 44', which are readily accessible for finishing operations, since a grinding or finishing tool may be fed across from one to another of them without 125 interference from the posts.

It will be evident that the annular character of the rests or surfaces within which the posts 34, 35 and 36 and 34', 35' and 36' engage the cap or cover and base members, 130

respectively, permits assemblage of the base and cap or cover without regard to the circumferential disposition of the posts.

Whereas, Figs. 2, 5 and 9 show my valves in closed position, the illustrations in Figs. 6 and 10 show the valve as open and ready for reverse movement.

In Figs. 9 to 12 I have illustrated my inlet valve which applies the same general principles as those set forth, but in which, to reduce the clearance upon the side toward the cylinders, I have reversed the faces which are operative as valve faces, utilizing the stiffening flanges or edges for that purpose and, for the same reason, use a tension spring and spider for valve return instead of the compression springs preferred in my discharge valves.

The base 50 is apertured at any suitable places, 51, 52, for the free passage of the inlet air and carries a plurality of posts 35², 36², corresponding, generally, to the posts shown in Figs. 5 and 6 (since the base does not carry the valve seat in this form and corresponds more nearly to the cap or cover of Figs. 5 and 6). Because the valves are made effective at the outer end of this base, the edge is extended at 53 in the form of a cylinder instead of by spaced posts such as are shown at 34'. In order to relieve the valves 22' from excessive engagement with the walls of this cylinder, the walls are cut away on the inside except for successive positions corresponding to the posts 34 where the walls project radially toward the center to form guides 53'.

Since the valve faces are the edges 54, 55, 54', 55', 54'', I have not recessed the under sides of the valves in Figs. 9 and 10.

The posts 35², 36² fit into corresponding annular recesses 56, 57 and the cylinder 53 fits into a recess or depression 58, the construction corresponding in general to the depression of the base in Fig. 7 and resulting in annular projections 40², 41², 42², 43², 44² in the cap or cover which annular projections comprise the valve seats and are accessible for ready surfacing by a tool or stone passing over the entire surface in the same manner and to the same extent as are the annular recesses 40', etc., shown and described in connection with Figs. 7 and 8.

In order to reseat the valves after they have been opened, closing them to the position shown in Fig. 9 from that shown in Fig. 10, I have preferred to use a tension spring member instead of a compression spring member because the tension member could be located upon the outside rather than upon the inside, requiring less inside space for the spring and reducing the clearance at this point.

The particular construction of spring which I have shown uses a single spring 59 for this purpose retaining the spring

against tension at one end by means of a bolt 60 and securing it to the valve 24' and to a spider 61 by means of a bolt and nut 62. This draws the central valve upward and the spider is extended far enough to 70 engage the several annulæ 22' and 23' by spring fingers 63, 64 and draw them up to position at the same time. The fingers permit the several valves to have slight freedom for independent axial movement so that 75 each of the valves may accommodate itself to its own seat.

The cap or cover of this valve is apertured freely, as at 63, 64 and 65 to allow free influx of air.

In operation:—In the forms shown in Figs. 2 to 8, the air compressed within the cylinder forces the valves outwardly along the guiding posts, acting independently upon each valve; and each valve is independently 85 closed by its springs when the pressure ceases. In the form shown in Figs. 9 to 12 the atmospheric pressure is effective to force the valves inwardly along the guiding posts, when a condition of vacuum exists in that 90 end of the cylinder. All the valves are returned by the spring and spider.

It will be evident that the form in which my invention is embodied may be varied greatly by the engineer or designer in view 95 of the disclosures in this specification and that I should receive the benefit of all such changes within the scope of my invention as set forth in the claims herein.

It will be evident that the channeling of 100 the inlet valves, shown in Figs. 9 to 12, has the effect of recessing the face of these valves, since the edges of the flanges comprise the sealing edges of the valves. The effect is similar to that of the recessing of 105 the under side of the valve parts in Figs. 2 to 8 inclusive and produces the same advantage of reduction in the amount of surface to be finished.

It will be evident that the ties 29 and 30, 110 while crossing the annular valve openings, lie back of the edge valve seats and therefore form no interruption to the continuity of valve seat contour and little interruption to the flow of air through the valve at these 115 points.

Having thus described my invention, what I claim as new and desire to secure by Letters Patent is:—

1. In a device of the character stated, cap 120 and base members, one carrying annularly disposed valve seats and the other carrying spacing posts forming guides in combination with annular valves co-operating with the seats, and resilient means for pressing the 125 valves toward the seats.

2. In a device of the character stated, cap and base members, one of the members carrying relatively raised edge valve seats surrounding valve openings in combination 130

with separate channeled valves coöperating with the seats, guides for the valves extending from one of the members to the other within the space between the raised edge valve seats and resilient means for closing the valves.

3. In a device of the character stated, cap and base members, one of the members carrying relatively raised edge valve seats above valve openings and the other guiding and spacing posts fitting between the raised edge valve seats, in combination with valves fitting the seats and guided by the posts.

4. In a device of the character stated, cap and base members, one of the members having edge valve seats about valve openings, a channeled valve fitting against the seats and having the flanges of the channel perpendicular to the plane of the seats, in combination with guides for the valve extending from one of the members to the other in the space between the seats.

5. In a device of the character stated, a valve member presenting an annular opening and adjoining edge valve seats, in combination with an annular valve having an annularly recessed face upon the side toward the valve seats, presenting projecting valve edges, guides directing the valve edges into engagement with the edge valve seats, a cover, spacing means between the cover and valve member and spring means for pressing the valve away from the cover.

6. In a device of the character stated, a valve member presenting an annular opening and adjoining edge valve seats, in combination with an annular valve having a recessed face upon the side toward the valve seats presenting projecting circular valve edges, and cylindrical flanges upon the edges of the valve on the side away from the seats, a cover, spacing means between the cover and valve member and spring means for pressing the valve away from the cover.

7. In a device of the character stated, a valve base comprising annular raised valve seats in combination with a cover for said base, posts projecting from said cover and resting upon the base between the annular seats, a valve guided by said posts and springs engaging the valve and cover to normally close the valve.

8. In a device of the character stated, a valve base comprising spaced rings, connected at intervals, forming a central opening and outer annular openings, having edge valve seats adjoining the openings, in combination with a central cupped valve and

annular adjoining valves coöperating with the valve seats and recessed upon the valve faces to provide projecting annular valve edges.

9. In a device of the character stated, a valve base comprising spaced rings connected at intervals, forming a central opening and outer annular openings, having edge valve seats adjoining the openings, in combination with a central cupped valve and annular adjoining valves coöperating with the valve seats and recessed upon the valve faces to provide projecting annular valve edges and axially extending flanges upon the opposite sides of the valves in line with the extended edge valve portions.

10. In a device of the character stated, a valve base presenting rings connected at intervals to leave annular valve openings and a central valve opening and edge valve seats adjoining the openings in combination with posts forming guides, located in the space above said rings and between the edge valve seats, annular channeled valves and a central cupped valve engaging with said seats and guided by said posts and means for resiliently holding these valves against the seats.

11. In a device of the character stated, a valve member presenting an annular opening and adjoining edge valve seats in combination with an annular valve of channeled cross section engaging the edge valve seats, and a guide directing the edges of the channel into engagement with the edge valve seats.

12. In a device of the character stated, a valve member presenting an annular opening and adjoining edge valve seats, in combination with an annular valve therefor, of channeled cross section, engaging the valve seats and a guide for the valve directing the channel edges into engagement with the edge valve seats.

13. In a device of the character stated, a valve member presenting an annular opening and adjoining edge valve seats, in combination with an annular valve having flanges on one side engaging the seats and a stiffening rib extending axially from the plane of the valve in proximity to each edge of the annulus but on the opposite side from the flanges.
